(57) **CLAIM**

The ornamental design for a liquid medication container and oral dispenser, as shown and described.

DESCRIPTION

FIG. 1 is a front view of a liquid medication container and oral dispenser in accordance with the present invention with the closure shown in the open configuration;

FIGS. 2 and 3 are opposing side views thereof;

FIG. 4 is a top perspective view thereof; and,

FIG. 5 is a top view thereof with the closure in the open configuration.

The indicia shown in broken lines in the drawings illustrates that portion of the article that is environment; the indicia forms no part of the claimed design.
